UNITED STATES PATENT OFFICE

CARL L. WEYAND, OF WATERBURY, CONNECTICUT

EAVES TROUGH

Application filed March 9, 1929. Serial No. 345,772.

This invention relates to eaves troughs, and more particularly to an improved form of eaves trough having a high degree of longitudinal rigidity.

- 5 One object of the present invention is to provide an eaves trough of the above nature which may be constructed from a smaller amount of sheet metal than the former types of eaves troughs now in general use.
- 10 A further object is to provide a device of the above nature which will be simple in construction, inexpensive to manufacture, easy to install and manipulate, ornamental in appearance, and very efficient and durable in use.

With these and other objects in view there has been illustrated on the accompanying drawing one form in which the invention may be conveniently embodied in practice.

- 20 The single figure represents a fragmentary perspective view of the improved form of eaves trough.

In manufacturing the common type of eaves trough now in general use, it was necessary to bend a metal strip transversely around a longitudinal form—a process which was very laborious and expensive to carry out. Moreover, it was also necessary, in order to provide sufficient stiffness, to provide the curled 25 bead of the trough with a sharply-bent interior lip or rim, necessitating the use of an additional amount of metal, and thereby increasing the expense of manufacture.

- By means of the present invention, the 30 above and other disadvantages have been avoided. This has been accomplished by providing an eaves trough in which the outer bead of the trough is bent inwardly in such a manner that the plane tangent to the surface 35 of the trough body at the junction with said bead will pass substantially through the center of the bead. By means of this construction, a groove is formed at the junction between the trough body and the bead which 40 produces a much stiffer construction and thereby eliminates the necessity of forming a lip on the curled-in edge of the bead. This construction also permits the eaves trough to be manufactured by a rapid and inexpensive 45 process of longitudinal rolling instead of by

the slower and more expensive process of transverse bending formerly employed.

A further advantage of the present invention is that an eaves trough of equal capacity may be constructed from a narrower strip of 55 metal than was the case with former types. This is due to the fact that the upper portion of the trough body adjoining the bead which was vertical in the old style eaves trough, is now bent inwardly and forms a 60 part of the curved bead. Aside from the reduction in the expense of metal thus obtained, the trough is much stronger and neater in appearance and in use will be held in better alignment with adjoining troughs by reason of the groove formed therein.

In practice, it has been found that the new style eaves trough constructed as herein disclosed can be manufactured in a rolling machine at a rate greatly in excess of the maximum output of the old style eaves trough transverse beading machine which was only about 1,000 feet per hour.

Referring now to the drawing in which like reference numerals denote corresponding parts, the numeral 10 indicates the body section of the eaves trough, said section preferably being semi-cylindrical and terminating in a straight edge 11 on its inner side for attachment to the edge of a roof by any suitable means not shown. The outer edge of the eaves trough is provided with a substantially cylindrical curled-over bead 12, which instead of being tangent to the body section 10, as in the old form of eaves trough now in common use, is bent inwardly and so disposed that the plane tangent to the edge of the body section 10 will pass substantially through the center of said bead 12. A groove 13 is thus formed at the joint between the body section 10 and the bead 12.

The groove as herein shown is angular in shape but it will be understood that it is within the spirit of the present invention to employ a curved or other shape of groove. It will also be understood that the present invention is not to be limited to an eaves trough having a single outer bead, as herein disclosed, but two beads may be used within the 100

spirit of the invention, one on either edge of the body section of the trough.

The groove 13 permits the eaves trough to be manufactured by passing a strip of metal longitudinally through rolls, since the groove prevents the strip from slipping laterally as it passes through the rolls. The eaves trough may thus be produced rapidly and efficiently, whereas with the old style of eaves trough 10 having no strengthening groove, lateral slipping would occur and hence this method of production was not available

While there has been disclosed in this specification one form in which the invention may 15 be embodied, it is to be understood that this form is shown for the purpose of illustration only, and that the invention is not to be limited to the specific disclosure but may be modified and embodied in various other forms 20 without departing from its spirit. In short, the invention includes all the modifications and embodiments coming within the scope of the following claims.

Having thus fully described the invention, 25 what is claimed as new, and for which it is desired to secure Letters Patent, is:

1. In an eaves trough, a smoothly curved body section having a tubular stiffening bead rolled outwardly on its outer upper edge, said 30 bead being disposed inwardly to form a strengthening groove at the junction between said body section and said bead, and a longitudinal segment of said bead being positioned adjacent an outer side of said groove.

2. In an eaves trough, an upwardly concave body section adapted to provide a channel for the water draining from the eaves, a tubular bead rolled outwardly on one edge of said body section, said bead being bent 40 inwardly so that a line tangent to the body section at the point of connection of said bead will pass within the interior of said bead, and a longitudinal segment of said bead being positioned adjacent an outer side of said groove.

3. In an eaves trough, an upwardly concave body section adapted to provide a channel for the water draining from the eaves, a tubular bead rolled outwardly on one edge 50 of said body section, said bead being bent inwardly so that a line tangent to the body section at the point of connection of said bead will pass substantially through the center of said bead and a longitudinal segment of said bead being positioned adjacent an outer side of said groove.

4. In an eaves trough, an upwardly concave body section adapted to provide a channel 60 for the water draining from the eaves, a tubular bead rolled outwardly on one edge of said body section, the upper outer portion of said body section adjoining the bead being bent inwardly to form a stiffening groove 70 and a longitudinal segment of said bead be-

ing positioned adjacent an outer side of said groove.

In testimony whereof, I have affixed my signature to this specification.

CARL L. WEYAND.
